UNITED STATES PATENT OFFICE.

CHARLES W. POWELL, OF YPSILANTI, MICHIGAN.

BELT CLASPS.

No. 911,329.

Specification of Letters Patent. Patented Feb. 2, 1909.

Application filed June 15, 1908. Serial No. 438,456.

To all whom it may concern:

Be it known that I, CHARLES W. POWELL, a citizen of the United States, residing at Ypsilanti, county of Washtenaw, State of Michigan, have invented a certain new and useful Improvement in Belt-Clasps, and declare the following to be a full, clear, and exact description of the same, such as will enable others skilled in the art to which it pertains to make and use the same, reference being had to the accompanying drawings, which form a part of this specification.

This invention relates to belt clasps, and has for its object an improved device of this type, adapted to firmly clasp a belt or strap of leather at any desired point, and hold it against further unintended passage therethrough, without reliance upon or use of, holes punched in the leather.

20 In the drawings: Figure 1, is a vertical sectional elevation of the device, with the ends of a belt passed therethrough, and held in position by the parts thereof. Figs. 2 and 3 are perspectives of the parts of the metal buckle detached from one another, Fig. 2 showing especially the obliquely slidable tongue piece which is adapted to grip the leather.

1 indicates a sheet metal casing, flat and 30 rectangular in outline, near one end of one side of which is cut a transverse slot 2. Removably engaging within this casing is a frame piece 3, whose side portions are of just the height to fit between the broad side pieces 35 of the casing, and whose central tabular piece 4 is of a width just a trifle smaller than the interior breadth dimensions of the side pieces of the casing 1. Near one end is a complementary slot 5, which, when the frame is inserted within the casing, is adapted to register with the slot 2. When these two slots are in register, one end 6 of the strap is inserted at the end of the casing, next adjacent to the slots, and then passed through the same and 45 brought around upon itself to any desired distance for convenient and sightly fastening.

In each of the side pieces of the frame 3, are oblique slots 7, in which engage the 50 terminal bearings 8 of the slidable tongue piece 9, whose end adjacent thereto is bent substantially right angular therewith to constitute the strap-engaging edge 10. This tongue may be manually actuated by the 55 user's finger, seizing the end 11, and causing the entire tongue 9 to slide with respect to

the frame and to the inclosing casing within the limits set by the location and direction of the slots. The other or adjustable end of the strap is passed through the casing from 60 the end opposite to that in which the transverse slots 2 and 5 are located, and caused to pass the engaging edge 10, and so long as the movement of the strap through the casing is in this direction only, the tendency 65 is to slide both this engaging edge portion and the entire tongue 9 toward that face of the casing in which the slots 2 and 5 occur. When, however, a releasing pull is to be attempted and the adjustable end of the strap 70 is drawn toward the end 11 of the tongue, the natural tendency of the strap to fall against the bottom or slotted side of the casing actuates the engaging edge portion 10 from its position more or less near the end 75 of the oblique slot 7, adjacent the slots 2 and 5, and by frictional contact thereagainst draws it up toward the plane face of the casing. The progress of the edge portion in 80 this direction is interfered with by the strap end 12, and as the strain continues, is brought so far up in that direction as to form in effect a clamp, the other member being the upper side or face 13 of the belt clasp; it is held in this position very firmly, 85 and when once it is set, the stronger the pull thereupon the more tight the clamping engagement becomes. If, however, it is desired to release the same, the pressure of one's finger against the end 11 of the tongue 9 is 90 sufficient to force the engaging edge 10, guided as it is by the movements of the oblique slots 7, away from the strap 12, so that the loose end of the belt is now free to move without obstruction through the clasp 95 member.

What I claim is:—

1. A belt clasp, comprising an outer casing provided with a slot near one end, a frame member adapted to engage therein 100 and provided with a slot adapted to register with said slot in the outer casing, and having in its side walls slots arranged obliquely to the plane of the portion wherein the registering slot is located, and a tongue member having its possible path of travel limited by the engagement of projecting portions within said oblique slots, adapted to have its engaging edge contacted by said strap when pulled through the casing in one direction, whereby the tongue member is drawn 105 against the strap and the strap is held from 110

further movement with respect to the casing, substantially as described.

2. A belt clasp, having in combination with an outer casing, a frame adapted to engage therein, there being in each a slot adapted to register with that in the other for the engagement of one end of the belt therethrough, and the side pieces of said frame being provided with oblique slots, 10 and a tongue piece engaging in said slots and adapted to move therewith to a posi-

tion, whereby, in coöperation with the opposing face of the casing, that end of the strap passing therethrough is held from further movement with respect thereto, substantially as described. 15

In testimony whereof, I sign this specification in the presence of two witnesses.

CHARLES W. POWELL.
